UNITED STATES PATENT OFFICE.

IRA E. McCABE, OF CHICAGO, ILLINOIS.

SAFETY OVERLOAD DEVICE.

Application filed December 21, 1925. Serial No. 76,791.

This invention relates to improvements in overload safety devices and more particularly to a device of this character when employed in connection with a switch for controlling an electric circuit actuated by an expansible and contractable member.

It is an object of this invention to provide a safety device for electric switches which will operate to prevent burning out of the switch or the burning out of a motor when placed in circuit with the switch.

It is also an object of this invention to include in such safety device a heat generating element adapted to release the switch and open the circuit when the amperage exceeds a predetermined degree.

It is also an object of this invention to provide a heat element included in the circuit adjustable to allow a predetermined amperage of the circuit to normally pass therethrough and adapted to be so adjusted that an increase in the amperage to a predetermined degree will meet with sufficient resistance to generate the amount of heat necessary to release the safety device.

While the preferred form of this invention is illustrated upon the accompanying sheet of drawing, yet it is to be understood that minor detail changes may be made therein without detracting from the scope of the invention.

In the drawings:

Figure 1 is a view in front elevation of an embodiment of this invention as applied to a pressure-actuated mercury tube electric switch, with the cover removed.

Figure 2 is a top plan view of Figure 1, partly in section.

Figure 3 is a view in side elevation of Figure 1, with parts broken away or omitted, illustrating the construction of the safety device.

Figure 4 is a fragmentary detail view similar to Figure 1, illustrating the position in dotted lines assumed by the parts when the device has been operated by the normal expansion of the Bourdon tube.

Figure 5 is a similar view illustrating the position assumed by the parts when the device has been operated by an overload of current.

Figures 6 and 7 are views similar to Figures 5 and 6 of a modification in which Figure 7 illustrates the position assumed by the parts when the device has been operated by the normal expansion of the Bourdon tube and overload of current.

The embodiment of this invention, as illustrated, includes a casing 1 in which is mounted a Bourdon tube 2 the open end 3 of which is adapted to be connected to an instrumentality either directly or through a thermal bulb, which will cause the tube to be affected by variations in pressure or temperature of said instrumentality. The free end of the Bourdon tube is connected by a pivoted actuating link 4 to the operating member 5 of the snap movement mechanism for tilting a mercury tube switch 6 to open and close an electric circuit therethrough. Figure 1 also diagrammatically indicates an electric circuit between the source of electricity, the switch 6, and the electric motor M. As indicated, a lead L from the commercial source of electricity is connected to a binding post 7 upon the rear of the casing which binding post is connected by a flexible lead 8 to one terminal of the electric tube switch adjacent the end thereof. The other terminal of the switch adjacent the first terminal is connected by a flexible lead 9 to a binding post 10 on the back of the casing. This binding post is connected by leads 11 and 12 through the safety device, to be hereinafter described, to the binding post 13, which in turn is connected by a lead 14 to one pole of the motor M, the other pole being connected by the lead L' to the source of commercial current. The specific construction and operation of the mercury tube switch mechanism is fully described in my prior application Serial No. 585,698, filed September 1, 1922, and as its construction forms no part of the present invention need only be described in general terms.

A bracket 17 of heat-transmitting material, such as brass, is supported by three posts 18 from a supporting plate secured upon the back of the casing 1, having a portion 19 perpendicular thereto and supporting a cup 20 in which is rotatively mounted

2
a shaft 21 having a ratchet wheel 22 about the upper end thereof. The mercury tube tilting support 15 is provided with a plate 23 extending toward the back of the casing. 5 A safety actuating member in the form of a bell crank lever 24 is pivotally mounted upon the supporting plate at the rear of the casing to rotate about a pivot adjacent its apex with the longer arm extending over said extension 23 and the shorter depending arm connected by a coil spring 25 to the rear of the casing which will normally exert sufficient force upon the longer arm to rotate it about its pivot to engage the extension 23 and tilt 10 the mercury tube switch into open position, overcoming the switch mechanism normally holding the tube in closed position. A member 16 of resilient metal is attached to the lever 24 in prolongation of its shorter arm 15 and adapted to act as a pawl at its free end and engage the teeth of the ratchet wheel 22.

The ratchet wheel 22 is normally held in fixed relation to the cup 20 by a film of solder so that when the pawl is in engagement with the ratchet wheel 22 the mercury tube switch will be held against rotation and when the solder is melted the ratchet wheel may be rotated to release the pawl and allow the mercury tube switch to be tilted to its 20 open position.

Within a cylindrical casing 26 of lavite or other electric insulation mounted between the supporting posts 18 and between the bracket 17 and back casing are arranged a 25 plurality of super-imposed graphite disks 27. A strip of mica or other electric insulating material is interposed between the surface of the bracket 17 and adjacent graphite disk and a similar insulating medium is interposed between a movable member 28 mounted at the opposite end of the casing and the adjacent graphite disk. Said movable member 28 is adapted to impart pressure upon the series of super-imposed graphite disks by the adjustable screw-threaded shaft 29 passing through the rear of the casing. The lead 11 from the binding post 10 is placed in electrical connection with the graphite disk at one end of the series and the lead 12 from the binding post 13 is placed in electric connection with the graphite disk at the other end of the series, so that when the circuit is closed through the mercury tube switch 6 the commercial current passes in series, first through the mercury tube then through the series of graphite disks to the motor.

As illustrated, the normal position of the long arm of the bell crank lever 24 when the pawl is in engagement with the ratchet allows the support 15 of the mercury tube switch to be rotated about the pivot of the operating mechanism by the expansion or contraction of the Bourdon tube and when 65 the pawl is released by the rotation of the

ratchet wheel if the mercury tube switch is in the closed position the lever 24 will contact with the extension 23 and rotate the support 15 about its pivot to the open position.

It is recognized in the electrical art that a series of super-imposed graphite disks will act as a conductor for electricity and the resistance to the current passing therethrough and the generation of heat thereby is in inverse proportion to the amount of pressure applied to the series of disks. In this embodiment of this invention the pressure upon the series of graphite disks 27 may be so regulated by the shaft 29 passing through the rear of the casing that a commercial current of predetermined amperage may pass therethrough to the mercury tube switch without encountering resistance enough to generate sufficient heat to melt the solder in the cup 20 holding the ratchet wheel shaft 21 and upon increase of the amperage to a predetermined degree the resistance created by the series of graphite disks will generate sufficient heat to melt the solder and allow the spring pressed bell crank lever 24 to operate to throw the switch into the open position and thereby break the commercial circuit through the motor.

In order to return the parts to normal 95 after having been operated by an overload of current to release the safety device and the amperage and voltage have decreased to or below the predetermined degree, a manual resetting device is provided which comprises a pin 30 mounted upon the lever 24 adapted to be engaged by a cam 32 upon the shaft of a hand reset button 31 projecting through the back of the casing, which upon manual rotation will lift the long arm of the lever 24 and cause the pawl 16 to again engage the ratchet wheel 22.

In the form illustrated in Figures 1, 4 and 5, the parts are so arranged that the free end of the longer arm of the bell crank lever 24 will, when released, engage the plate 23 to throw the switch tube into the open position. In Figures 4 and 5 the under side of this longer arm is cut away between its free end and pivoted apex to provide a 110 depending nose 33 and heel 34 and the plate 23 is secured to the mercury tube support 15 in such a manner that when an overload of current releases the lever 24, the nose 33 thereof will engage the plate 23 which will 115 pass free of the heel 34 in throwing the switch tube into the open position.

In Figures 6 and 7 the mercury tube switch is caused to close the circuit therethrough upon the normal expansion of the Bourbon tube by reversing the position of the mercury tube, that is, by inserting the tube in the supporting clips with the terminals at the right of the casing. In this case the plate 23 is secured to the mercury 120

tube support 15 in such a manner that when an overload of current releases the lever 24, the heel 34 thereof will engage the plate 23 which will pass free of the nose 33 in 5 throwing the switch tube into the open position.

While this embodiment has illustrated and described the series of superimposed disks forming the heat generating unit of varying conductivity in inverse proportion to pressure placed upon the disks as being formed of graphite, it is to be understood that other materials such as carbon or compositions of material that will act as electrical conductors, may be used in place of the graphite disks to produce the same result.

What I claim is:

1. A safety device for an electric circuit 20 to prevent an overload therethrough comprising in combination with a mechanically-operated electric switch, an additional mechanical actuator therefor adapted to open the switch to open the circuit therethrough 25 detachably held in inoperative position by a thermal connection, electric means in circuit with said switch and source of electricity comprising a plurality of superimposed discs adapted to be actuated by an increase 30 in current passing therethrough increasing the temperature thereof to release said holding means and allow the switch to be operated to break the circuit therethrough.
2. A safety device for an electric circuit 35 to prevent an overload therethrough comprising in combination with a mechanically-operated electric switch, an additional mechanical actuator therefor adapted to open the switch to open the circuit therethrough 40 detachably held in inoperative position by a thermal connection, electric means in circuit with said switch and source of electricity adjustable to a predetermined conductivity 45 adapted to be actuated by an increase in current passing therethrough to generate heat sufficient to release said holding means and allow the switch to be operated to break the circuit therethrough.
3. A safety device for an electric circuit 50 to prevent an overload therethrough comprising in combination with a mechanically-operated electric switch, an additional mechanical actuator therefor adapted to open the switch to open the circuit therethrough 55 detachably held in inoperative position by a thermal connection, electric means including a plurality of superimposed discs of varying conductivity so adjusted as to be actuated by an increase in current passing therethrough whereby the resistance offered generates sufficient heat to release said holding means and allow the switch to be operated to break the circuit therethrough.
4. A safety device for an electric circuit 60

to prevent an overload therethrough comprising in combination with a mechanically-operated electric switch, an additional mechanical actuator therefor adapted to open the switch to open the circuit therethrough 70 detachably held in inoperative position by a thermal connection, electric means including a plurality of superimposed discs of conductive material, the conductivity of which varies in accordance with the pressure 75 applied thereto, and the pressure so adjusted as to be actuated by an increase in current passing therethrough whereby the resistance offered generates sufficient heat to release said holding means and allow the switch to be operated to break the circuit therethrough.

5. A safety device for an electric circuit 80 to prevent an overload therethrough, comprising in combination with a mechanically-operated electric switch having a tilting movement about a pivot, an additional mechanical actuator therefor comprising a pivoted actuating lever normally adapted to engage and rotate said switch to open the circuit therethrough, said actuating lever 85 detachably held in inoperative position by a thermal connection, electric means in circuit with said switch and source of electricity comprising a plurality of superimposed discs 90 adapted to be actuated by an increase in temperature passing therethrough increasing the temperature thereof to release said holding means and allow the switch to be operated to break the circuit therethrough.

6. A safety device for an electric circuit 95 to prevent an overload therethrough comprising in combination with a mechanically-operated pivoted electric switch, an additional mechanical actuator therefor comprising 100 a pivoted actuating lever normally adapted to engage and rotate the electric switch about its pivot to open the circuit therethrough, said actuating lever detachably held in inoperative position by a thermal connection, electric means including a plurality of superimposed discs of conductive material, the conductivity of which varies with the pressure applied thereto, and the pressure so adjusted as to be actuated 105 by an increase in current passing therethrough, whereby the resistance offered generates sufficient heat to release said holding means and allow the switch to be operated to break the circuit therethrough.

7. A safety device for an electric circuit 110 to prevent an overload therethrough comprising in combination with a mechanically-operated pivoted electric switch, an additional mechanical actuator therefor comprising 115 a pivoted actuating lever normally adapted to engage and rotate the electric switch about its pivot to open the circuit therethrough, said actuating lever detachably held in inoperative position by a ther-
